DESIGN FOR A LANTERN

Frederick B. Embury, Warsaw, N. Y., assignor to Embury Manufacturing Company, Warsaw,
N. Y., a corporation of New York

Application November 15, 1939, Serial No. 88,286

Term of patent 14 years

To all whom it may concern:

Be it known that I, Frederick B. Embury, a citizen of the United States, residing at Warsaw, in the county of Wyoming and State of New York, have invented a new, original, and ornamental Design for a Lantern, of which the following is a specification, reference being had to the accompanying drawing, forming part thereof.

Fig. 1 is a plan view of a lantern, showing my new design, and
Fig. 2 is a side elevational view thereof.

I claim:

The ornamental design for a lantern, substantially as shown.

FREDERICK B. EMBURY.
